a corporation of Illinois

Application April 11, 1941, Serial No. 388,041

4 Claims. (Cl. 62—116)

The present invention relates to refrigerating systems in which several cooling units are employed to maintain various temperature levels in the respective compartments in which such cooling units are located.

Since these cooling units have a circulation of a volatile refrigerant, by means of a common compressor evacuating refrigerant vapor therefrom and furthermore since the pressure, of the volatile refrigerant, is proportional to its temperature the present invention contemplates closing the vapor outlet of the higher temperature cooling units whenever they have reached their desired temperature as reflected by the pressure of the volatile refrigerant.

Previous multi-temperature refrigerating systems were controlled by means of thermostatically operated solenoid valves, snap action suction line control valves or mere pressure throttling valves. All of such systems had the common defect that the higher temperature cooling units might cut into the circuit long before the lowest temperature cooling unit arrived at its desired low temperature. In such cases it is impossible to maintain the low temperatures desired since the volatile refrigerant pressure, in the low temperature units, would be much less than the volatile refrigerant pressure in the higher temperature cooling units.

An object of the present invention is to provide an improved multi-temperature refrigerating system in which the various cooling units will cut out of the refrigerant circuit as their various desired temperatures are reached.

Another object of the invention is to provide an improved multi-temperature refrigerating system in which the higher temperature cooling units cannot cut into the refrigerant circuit until the demands of the lowest temperature cooling unit is satisfied.

A further object of the invention is to provide a new type of refrigerant suction line cut off valve as used in the invention.

Referring to the drawings:

Fig. 1 is an elevational cross sectional view of the suction line cut off valve as used in the multi-temperature refrigerating system.

Fig. 2 is a cross sectional view along line 2—2 of Fig. 1.

Fig. 3 is a cross sectional view of a suction line check valve as used on the suction line of the lower temperature cooling units.

Fig. 4 is an elevational view, partly in section, of a suction line pressure operated starting and stopping switch.

Fig. 5 is a diagrammatic view of a multi-temperature refrigerating system embodying the invention.

Fig. 6 is a chart showing the operating characteristics of a typical multi-temperature system, such as Fig. 4, embodying the invention.

In the drawings:

In Figs. 1 and 2, the suction line cut off valve 1 comprises a casing 8 having an inlet 9 and an outlet 10 between which is disposed a valve 11 having a small leak orifice 12. The valve 11 engages a seat 13, in the casing 8, under the urging of the diaphragm 14 which is pressed downwardly by means of the diaphragm spring 15. The pressure of the refrigerant, at the outlet 10, tends to press the diaphragm 14 upwardly, against the force of the spring 15, and the valve spring 16 tends to move the valve 11 upwardly and open the full passage between the inlet 9 and outlet 10.

A cover 17, screw threaded to the casing 8, at 18, clamps the diaphragm 14 thereto and serves as an abutment for the non-rising stem adjusting screw 19, the upper end of which projects through the bore 20 of the cover 17.

The cover 17 has two slots 21 loosely engaging the lugs 22 of the spring seat 23 which is threadedly engaged by the adjusting screw 19, whereby turning of the adjusting screw 19 results in lengthening or shortening of the diaphragm spring 15 and consequently decreasing and increasing respectively the amount of spring pressure exerted upon the diaphragm 14.

The adjusting screw 19 has a central bore 24 in which a feeler pin 25 loosely plays. In the fabrication of this cut off valve 1, I engage the valve 11 with its seat 13 and then make the feeler pin 25 of such length that it is even with the top 26 of the adjusting screw 19, which, being of the non-rising stem type, will always indicate the amount that the valve 11 is open by the amount that the feeler pin 25 projects above the top 26. This furnishes a readily evident means for determining the correct point of adjustment.

In Fig. 3, the check valve 33 is of a rather common type, widely available, in which a flow between the inlet 34 and the outlet 35 opens the valve 36 which is pressed against its seat 37 by means of the spring 38. Whenever the pressure, at the outlet 35, equals or exceeds the pressure at the inlet 34, the valve 36 stays closed thereby preventing a reversal of the fluid flow.

In Fig. 4, the suction line pressure operated starting and stopping switch 44, which herein-after for purposes of brevity will be termed pres-

surestat, comprises a casing 45 in which is mounted a bellows 46, having a capillary tube 47, which contacts a lever arm 48 pivoted at 49. An adjusting screw 50, threadedly engaging the casing 45, presses upon a spring support 51 serving as one abutment of the spring 52, whose other end presses down upon the lever arm 48. In consequence the adjustment, of the adjusting screw 50, serves to vary the pressure necessary, within the bellows 46, in order to move the lever arm 48.

The free end, of the lever arm 48, carries a contact 53 to which is connected an electrical conduit 54. The casing 45 has mounted thereon a stationary contact 55 to which is connected an electrical conduit 56. The movement of the lever arm 48, under the influence of the pressure within the bellows 46, makes and breaks an electrical circuit between the contacts 53 and 55, a rising pressure tending to make the electrical circuit and vice versa.

In Fig. 5, the multi-temperature refrigerating system comprises the refrigerated compartments 66, 67 and 68 in which are placed the cooling units 69, 70 and 71 respectively, which have suction lines 72, 73 and 74 respectively connected to a common suction line 75 from which refrigerant vapor is evacuated by means of the compressor 76 driven by the electric motor 77 under the control of the pressurestat 44 which makes and breaks the electrical circuit responsive to the pressure conditions within the suction line 75 to which the capillary tube 47 is connected as shown.

The compressor 76 compresses the refrigerant vapor into the condenser 78 in which it surrenders heat and becomes liquified. The liquid refrigerant leaves the condenser 78 by means of the liquid conduit 79 from which supply conduits 80, 81 and 82 serve to feed the thermal expansion valves 83, 84 and 85, which in turn feed refrigerant liquid to their respective cooling units responsive to superheat conditions, of the refrigerant vapor, at the points to which their respective temperature feeler bulbs 86, 87 and 88 are clamped as shown.

Since thermal expansion valves are well known and so universally used throughout the art, it will suffice to state that they tend to feed refrigerant liquid, to a cooling unit, in such quantity and at such rate of flow that the vapor, leaving such cooling unit, will have some definite degree of superheat. As the compartment temperatures drop, the thermal expansion valves necessarily decrease the rate of refrigerant feed to the cooling units, consequently the refrigerant pressures, within the cooling units, also correspondingly drops.

The outlet, of the cooling unit 69, connects to a cut off valve 7 which in turn connects to the suction line 72.

The outlet, of the cooling unit 70, connects to a cut off valve 7 which in turn connects to the suction line 73 in which is mounted a check valve 33. The outlet, of the cooling unit 71, connects to the suction line 74 in which is mounted a check valve 33.

We shall assume that the refrigerant used is methyl chloride, that compartment 66 shall be 33° F. with a 10° F. temperature of the cooling unit 69, that compartment 67 shall be 5° F. with a -10° F. temperature of the cooling unit 70, that compartment 68 shall be -2° F. with a -20° F. temperature of the cooling unit 71.

Assuming the system at rest and the vapor

pressure building up in the suction line 75, as shall be explained later. The suction cut off valves 7 are assumed to be open. The pressurestat 44 is adjusted to make contact, and establish the current flow to the motor 77, whenever the pressure increases to 24 lbs. per square inch gauge, which, for methyl chloride, is equivalent to a temperature of 35° F.

The compressor 76 now starts up and evacuates vapor from the suction line 75. At this time the refrigerant pressure, within the suction line 75, is generated solely within the cooling unit 69.

Referring to the chart, Fig. 6, indicates the starting point at D, which is 24 lbs. pressure. The line D to E indicates that the pressure, within the cooling unit 69, over a period of approximately 10 minutes elapsed compressor running time, drops to 8 lbs., giving a temperature of 10° F. to the cooling unit 69. The particular cut off valve 7 is now adjusted to close off at 8 lbs. pressure.

At this time the pressure, within the cooling unit 70, is approximately 4 lbs. and the suction line 75 readily evacuates to this value as indicated by the line E to F at which time the check valve 33 allows a flow therethrough. The line F to G indicates that the pressure, within the cooling unit 70, drops to 0 lb. gauge, during an elapsed compressor running time of approximately 9 minutes, which gives a -10° F. temperature to the cooling unit 70. The respective cut off valve 7 is now adjusted to close off at 0 lb. gauge pressure.

At this time the pressure, within the cooling unit 71, is 1" vacuum to which the suction line readily evacuates as indicated by the line G to H. The check valve 33, serving the cooling unit 71, now opens, and the pressure, within the cooling unit 71, drops to 5" vacuum during 7½ minutes operating time of the compressor, as indicated by line H to A. At this point the temperature, of the cooling unit 71, is down to -20° F. and the pressurestat 44 is now adjusted to break the electrical circuit and close down the compressor 76.

From the above description, it will be evident that I provide, where the temperature differences, between the various cooling units, are wide enough, means for the compressor to operate upon only one unit at a time, the various units cutting out of circuit progressively.

During the compressor operation, upon the cooling units 70 and 71, there is a slight vapor escape through the leak orifice 12 of the respective cut off valve 7, connected to the cooling unit 69. This same condition also exists with the particular cut off valve 7, connected to the cooling unit 70, whenever the compressor is operating upon the cooling unit 71.

This leakage is relatively unimportant from the standpoint of seriously affecting the compressor capacity when operating upon the lowest temperature unit 71.

When the compressor closes down, both of the cut off valves 7 are leaking into the suction line 75, as indicated by lines A to B. At point B the cut off valve 7, connected to cooling unit 70, opens wide. At some point, intermediate between B and C, the pressure, within the suction line 75, equals the pressure in the cooling unit 70 and then its associated check valve 33 closes and prevents a reverse pressure flow into the cooling unit 70.

At point C the cut off valve 7, connected to cooling unit 69, opens wide and the pressure, within the suction line 75, takes a big jump to

approximately 22 lbs. pressure. During a lapse of approximately 7½ minutes the pressure, within the cooling unit 69 and the suction line 75, reaches a value of 24 lbs., due to the temperature increase of the cooling unit 69, and the pressurestat 44 again starts the compressor, and the previously explained operating cycle, as indicated by line D to A, recurs.

While the above description relates to a particular system operated under particular conditions of compartment and cooling unit temperatures and with a particular refrigerant, it will be readily evident, to those versed in the art, that many variations may be employed without departing from the spirit and scope of the invention, which is to be limited only to the hereto appended claims.

I claim:

1. In a multi-temperature refrigerating system comprising a plurality of compartments to be maintained at certain temperatures by means of the circulation of a volatile refrigerant, between the inlet and outlet of cooling units disposed in said compartments, responsive to a single refrigerant compressor means controlled to start upon some certain high suction pressure generated by the cooling unit in the compartment of highest temperature and controlled to stop upon some certain low suction pressure developed during the operation of said compressor upon the cooling unit in the compartment of lowest temperature, the combination of automatic valve means, at the outlets of the higher temperature cooling units, responsive to lowering suction pressure, during the operation of said compressor, to progressively check the outlet flow of first the highest temperature cooling unit, second the next highest temperature cooling unit and so on in a temperature descending scale.

2. In a multi-temperature refrigerating system comprising a plurality of compartments to be maintained at certain temperatures by means of the circulation of a volatile refrigerant, between the inlet and outlet of cooling units disposed in said compartments, responsive to a single refrigerant compressor means controlled to start upon some certain high suction pressure generated by the cooling unit in the compartment of highest temperature and controlled to stop upon some certain low suction pressure developed during the operation of said compressor upon the cooling unit in the compartment of lowest temperature, the combination of automatic valve means, at the outlets of the higher temperature cooling units, responsive to lowering suction pressure, during the operation of said compressor, to progressively check the outlet flow of first the highest temperature cooling unit, second the next highest temperature cooling unit

and so on in a temperature descending scale, said automatic valve means substantially but not wholly restricting all flow therethrough when in closed position.

5 3. In a multi-temperature refrigerating system comprising a plurality of compartments to be maintained at certain temperatures by means of the circulation of a volatile refrigerant, between the inlet and outlet of cooling units disposed in said compartments, responsive to a single refrigerant compressor means controlled to start upon some certain high suction pressure generated by the cooling unit in the compartment of highest temperature and controlled to 10 stop upon some certain low suction pressure developed during the operation of said compressor upon the cooling unit in the compartment of lowest temperature, the combination of automatic valve means, at the outlets of the higher 15 temperature cooling units, responsive to lowering suction pressure, during the operation of said compressor, to progressively check the outlet flow of first the highest temperature cooling unit, second the next highest temperature cooling unit 20 25 and so on in a temperature descending scale, said automatic valve means substantially but not wholly restricting all flow therethrough when in closed position, and check valves in the outlets of the lower temperature cooling units.

30 4. In a multi-temperature refrigerating system comprising a plurality of compartments to be maintained at certain temperatures by means of the circulation of a volatile refrigerant, between the inlet and outlet of cooling units disposed in said compartments, responsive to a single refrigerant compressor means controlled to start upon some certain high suction pressure generated by the cooling unit in the compartment of highest temperature and controlled to stop upon some certain low suction pressure developed during the operation of said compressor upon the cooling unit in the compartment of lowest temperature, the combination of automatic valve means, at the outlets of the higher temperature cooling units, responsive to lowering suction pressure, during the operation of said compressor, to progressively check the outlet flow of first the highest temperature cooling unit, second the next highest temperature cooling unit and so on in a temperature descending scale, said automatic valve means substantially but not wholly restricting all flow therethrough when in closed position, and check valves in the outlets of the lower temperature cooling units, and said cooling units being fed, with refrigerant fluid, by means of superheat controlled expansion valves.

ANTHONY F. HOESEL.
